United States Patent Office

Des. 192,190
Patented Feb. 6, 1962

192,190

BOTTLE

Clifford R. Wheeler, Agawam, Mass., assignor to Custom
Plastics Corporation, Chicopee, Mass., a corporation

Filed May 18, 1961, Ser. No. 65,220

Term of patent 14 years

(Cl. D58—6)

FIG. 1

FIG. 2

FIG. 1 is a side elevational view of a bottle, embodying my new design;

FIG. 2 is an end elevational view; and

FIG. 3 is a top plan view thereof.

The end and side not illustrated are the same as the end and side which are illustrated.

I claim:

The ornamental design for a bottle, as shown and described.
